PRINTER-PROJECTION SYSTEM

David F. Newman, Rockville Centre, N. Y., assignor to Trans-Lux Corporation, New York, N. Y., a corporation of Delaware

Application August 26, 1938, Serial No. 226,992

3 Claims. (Cl. 88—24)

My invention relates to a combined printer-projection system.

In accordance with my invention, a printing wheel is related to a projecting field in such manner that the line of characters printed transversely on a web coincides with the plane of said printing wheel as the latter proceeds with the printing operation.

My invention has further reference to a system of the character described wherein the web receiving the printed characters is movable step-by-step through a projection field, each step of said web effecting the movement into said projection field of the last line of characters printed by the printing means.

My invention has further reference to a combined printer-projection system wherein the printing wheel arrangement is provided with a plurality of peripheral rows of characters, said printing wheel being shiftable into alternate positions so that the printing may be effected from either row of characters as desired.

Various other objects, advantages and features of my invention will become apparent from the following detailed description.

My invention resides in the printer-projection system, the novel printing wheel arrangement and its relation to a projection field, features and combinations of the character hereinafter described and claimed.

For an understanding of my invention and for an illustration of one of the many forms thereof, reference is to be had to the accompanying drawing, in which:

Figure 1 is a side elevational view of a printer-projection system as constructed in accordance with my invention;

Fig. 2 is a front elevational view of the printer-projection system shown in Figure 1; and

Fig. 3 is a perspective view illustrating a feature of the invention.

Referring to the drawing, I have illustrated a projecting system suitable for projecting images from a web of the type hereinafter described. As herein shown although not necessarily, the aforesaid projecting system may comprise a suitable source of light 1 with which may be associated a reflector 2 whereby a beam of light is projected from right to left, Fig. 1, so as to pass through one or more condenser lenses 3, 4. After passing beyond the condenser lens 4, the projecting light beam passes through a projection aperture or field 5a formed in a plate or member 5, the beam of light thereafter being deflected upwardly by a mirror 6 and then passing

through a suitable objective lens 7. Beyond this objective lens, the projecting light beam engages any suitable mirror system, not shown, and then passes to the projection screen.

5 Printing devices such, for example, as a Dow-Jones news ticker as described in U. S. Letters Patent No. 1,972,466 or a Burry news ticker as described in U. S. Letters Patent No. 680,693, are well known to the art wherein a rotatable type wheel is moved step-by-step transversely of a wide web so as to print information in lines extending transversely thereof. Those skilled in the art are familiar with the mechanical and electrical operating arrangements utilizable in 10 such printing devices for rotating the type wheel to a selected position, moving the type wheel step-by-step transversely of the web, and moving the web a line space after each line has been printed, these various operating arrangements 15 usually being remotely controlled from a central station. While my invention relates generally to such operating arrangements, I am not concerned with the details thereof since, as stated, they are well known to the art.

20 Accordingly, in explanation of my invention, I have merely illustrated a casing C which is to be understood as containing various operating arrangements, as aforesaid. Supported by the casing C is a horizontal member 10 on which is 25 slidable a sleeve or carriage 11 from which up-stands one or more members 12 terminating in an upper bearing 13. Extending vertically past the sleeve 10 and through the bearing 13 is a shaft 14 which, at its upper end, carries a suitable type wheel 15 with which is associated an inking roller 16 carried by a bracket arm 17 secured, for example, to one of the aforesaid members 12. Coactable with the type wheel 15 is a platen 18 of the usual character known to the art, said platen 18 being secured at each of its ends to an arm 19 and the arms 19 being pivoted for oscillatory movement in suitable manner as known to the art.

30 Supported in suitable manner is a member, not shown, upon which is wound a web W formed from suitable transparent or semi-transparent material such, for example, as Cellophane or glassine paper. Extending upwardly from the aforesaid roll is a web or web section W which passes between the type wheel 15 and the platen 18, and is disposed adjacent the aperture 5a, said web W thereafter extending upwardly between the pulling or drawing rollers 20 and 21, the 35 roller 21 having connected thereto a suitable

shaft 22 whereby the web W may be moved step-by-step through the projection field 5a.

Assuming that the carriage 11 is positioned in line-starting position at the extreme end of the projection field 5a toward the left, Fig. 2, the operator, by a control suitably effected on the known mechanism, causes rotation of the shaft 14 whereby the printing wheel 15 is rotated to position the selected character opposite the platen 18. Thereupon, by operation of the known mechanism, the platen 18 is moved by a snapping action from right to left, Fig. 1, to thereby thrust the adjacent web section against the selected character and print a representation thereof on the web W. Immediately thereafter, the carriage 11 and the thereby-carried parts are moved a letter space from left to right, Fig. 2, by operator actuation of the rack bar mechanism 26a by the pawls 25, 26, this mechanism corresponding with the similar mechanism of the Dow-Jones printer and being actuatable and operable in generally the same manner. In this manner, the printing operation proceeds letter-by-letter until all or a desired part of a line of characters is printed.

Thereupon, by operator control and in generally the same way as existing type wheels are returned to initial position, the carriage 11 and associated parts are returned to initial position and, simultaneously, in known manner, the shaft 22 is actuated to impart a step of rotative movement to the roller 21 in a clockwise direction, Fig. 1, whereby the web W is moved a line space past the printing wheel 15 and the projection field 5a. Thereafter, in the manner hereinbefore described, the succeeding line of information is printed transversely of the web W.

In view of the foregoing, it follows that lines of information are printed in succession on the web W and that such lines of information pass into and through the projection field 5a. While in said projection field images of such lines are projected onto the screen in enlarged form for visual observation as desired.

An important feature of my invention relates to the position taken by the printing wheel 15. With prior art printers, the printing wheel is disposed in a vertical plane and, therefore, if an image of said printing wheel is not to be projected, it necessarily follows that said printing wheel must be positioned below the projection field. Due to the vertical disposition thereof, it results, therefore, that there is a substantial length of web between the printing position and the bottom of the projection field. This substantial length of web carries a plurality of printed lines and, accordingly, with prior art practice, substantial delay occurs between the printing and projecting operations.

By my invention, the printing wheel 15 is positioned in a horizontal plane or substantially so and, with a vertical projection field, the plane of said printing wheel is at right angles to the plane of said projection field. This is illustrated in Fig. 3 wherein the plane P of the printing wheel 15 is disposed at right angles with respect to the web section in the projection field, said plane of the printing wheel being that plane which passes through the rim or periphery thereof and is disposed at right angles to the axis of rotation of said printing wheel. Accordingly, the horizontal printing wheel of my invention may be positioned extremely close to the bottom of the projection field and, even so, there is no projection of an image thereof.

As indicated in Fig. 2, a plurality of printed lines are in the projection field 5a and the printing wheel 15 is printing the next line. As soon as this line is printed, the subsequent operation of the web-drawing rollers 20, 21 moves the line just printed into said projection field. This is highly desirable, although it shall be understood that my invention is not to be so limited, because contributing to the quick release of news items.

An added feature of my invention relates to the provision of a printing wheel 15 having a plurality of peripheral rows of characters. With such an arrangement, the printing wheel is necessarily movable to alternate positions depending upon the particular row of characters in which a selected character is to be found. In order thus to position said printing wheel 15 in alternate vertical positions, the shaft 14 is so mounted in its bearings that it may be vertically adjustable. Carried by the shaft 14 are a plurality of spaced collars 28, 29 with which is co-actable a pivoted lever 30 utilized for moving the shaft 14 to a desired vertical position and retaining the same in said position. It will be understood that this lever 30 may be suitably actuated under remote or other control for the desired purpose.

From the foregoing description, it will be understood that I have diagrammatically illustrated various well known devices and expedients of the printer and projecting arts. Thus, it is well known that, for satisfactory projection, a retarding force should be applied to the web just as it enters the projection field. With the present form of my invention, I have shown the member 5 as comprising oppositely disposed spring sections 5b, 5b which engage the web W at the bottom of the projection field and hold it against the member at the opposite side of the web W for the purpose specified. Further, it will be understood that the printing wheel 15 may be equipped with a suitable known mask, not shown, whereby, upon operation of the platen, only the selected character is printed without smudging by the adjacent characters.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In combination, printing means comprising a printing wheel for printing lines of characters transversely on a transparent or translucent web, means for drawing said web upwardly from said printing wheel, said drawing means being spaced above said printing wheel to such extent that there is formed therebelow a substantially vertical projection field having sufficient height to receive several of the printed lines at a given time, means comprising a projecting system for passing a projecting light beam substantially horizontally through said projection field, said projecting system comprising a condenser lens at one side of said projection field and an objective lens at the other side thereof, and means comprising a shaft remaining continuously in a vertical position on which said printing wheel is rotatively supported in a horizontal plane, the plane of said printing wheel coinciding with each

printed line as the latter is printed, the horizontal plane of said printing wheel as it prints on the web being disposed substantially at right angles to the substantially vertical plane of said projection field.

2. In combination, printing means comprising a printing wheel for printing lines of characters transversely on a transparent or translucent web, means for drawing said web upwardly from said printing wheel in step-by-step fashion, said drawing means being spaced above said printing wheel to such extent that there is formed therebelow a substantially vertical projection field having sufficient height to receive several of the printed lines at a given time, means comprising a projecting system for passing a projecting light beam substantially horizontally through said projection field, said projecting system comprising a condenser lens at one side of said projection field and an objective lens at the other side thereof, and means comprising a shaft remaining continuously in a vertical position on which said printing wheel is rotatively supported in a horizontal plane, the plane of said printing wheel coinciding with each printed line as the latter is printed, the horizontal plane of said printing wheel as it prints on the web being disposed substantially at right angles to the substantially vertical plane of said projection field, said printing wheel being disposed below said projection field and spaced from the bottom thereof a distance

less than a single step of movement of said web.

3. In combination, printing means comprising a printing wheel for printing lines of characters transversely on a transparent or translucent web, said printing wheel being rotatably mounted and having a plurality of peripheral rows of characters thereon, means for shifting said printing wheel to alternate positions whereby the printing operation may be effected from a desired row of said characters, means for drawing said web upwardly from said printing wheel, said drawing means being spaced above said printing wheel to such extent that there is formed therebelow a substantially vertical projection field having sufficient height to receive several of the printed lines at a given time, means comprising a projecting system for passing a projecting light beam substantially horizontally through said projection field, said projecting system comprising a condenser lens at one side of said projection field and an objective lens at the other side thereof, and means comprising a shaft remaining continuously in a vertical position on which said printing wheel is rotatively supported in a horizontal plane, the plane of said printing wheel coinciding with each printed line as the latter is printed, the horizontal plane of said printing wheel as it prints on the web being disposed substantially at right angles to the substantially vertical plane of said projection field.

DAVID F. NEWMAN.
